CABLE GRIP

Wilbur T. Gloor, Berwyn, Pa., assignor, by mesne assignments, to The Warner & Swasey Company, Cleveland, Ohio, a corporation of Ohio

Filed June 10, 1963, Ser. No. 286,680

3 Claims. (Cl. 73—103)

The present invention relates to cable snubbing grips and especially to cable snubbing grips for securing specimens of cables tested in tension.

A purpose of the invention is to eliminate the need for special end preparation of cable tested in a tensile testing machine.

A further purpose is to eliminate the need for socketing the ends of cable used in a testing machine.

A further purpose is to gradually reduce the tensile force in a cable as it passes around the grip so that the tensile force is minimal at a cam lock.

A further purpose is to use the grips in pairs, one at each end of the cable.

A further purpose is to provide grips from which the cable can be readily removed at the conclusion of the test.

A further purpose is to force a cantilever element toward an eccentric cam and increase the clamping force on the cable.

A further purpose is to utilize the drag of a cable through the cam lock to rotate the lock so that it increases its clamping force.

A further purpose is to fix each of two grips to a tension-load-applying element of a testing machine.

A further purpose is to allow the user to mount the grips in a testing machine at a specific distance between the tangent points of the drums.

A further purpose is to permit an adjustment to set an initial load in the specimen.

A further purpose is to provide a grip which works particularly well on stranded cable but can be used also on single wire like copper wire.

A further purpose is to provide a self energizing cam which tightens further as the cable pulls.

A further purpose is to deflect a cantilever lip to act against the cam like an anvil.

A further purpose is to position the axis of pull on the cable through the center of the cable.

Further purposes appear in the specification and in the claims.

In the drawings, I have chosen to illustrate two only of the numerous embodiments in which my invention may appear, selecting the forms shown from the standpoints of convenience in illustration, satisfactory operation and clear demonstration of the principles involved.

FIGURE 1 is a perspective view of a tensile testing machine utilizing the cable grips of the invention to grip a cable test specimen.

FIGURE 2 is a front elevational view of the cable grip of the invention.

FIGURE 3 is a sectional elevational view taken on the line 3—3 of FIGURE 2.

FIGURE 4 is a top plan view of the grip of FIGURE 2.

FIGURE 5 is a vertical section taken on the line 5—5 of FIGURE 3.

FIGURE 6 is a front elevational view of a modified form of the invention.

FIGURE 7 is an elevational section taken on the line 7—7 of FIGURE 6.

FIGURE 8 is a fragmentary rear elevational view of some of the components seen in FIGURES 6 and 7.

Describing in illustration but not in limitation and referring to the drawings:

Tensile testing machines which apply a tensile load

2

to a test specimen to establish a stress-strain relationship as well as a failure point are well known wherein the load applied to the specimen is measured by suitable gauging devices.

5 In using these testing machines, it is necessary to mount the specimen to the load applying elements by a gripping device which does not allow the specimen to slip. In the case of cable or wire rope specimens, it has been conventional, for instance, to apply molten metal to the end strands to enlarge the diameter. The enlarged end of the cable is then seated in a socket formed in the force supplying element of the testing machine.

Such socketing procedure is slow and expensive. By means of the present invention, the need to socket the cable test specimen is eliminated, and the cable may be quickly and easily mounted in the testing machine. The cable is merely wound around the outer circumference of a drum portion of a grip and then brought through an opening in the drum circumference to the inner circumference where it is engaged by an eccentric cam. By virtue of a cantilevered segment of the drum as well as the cam, the cable is securely held against slippage. Tension along the cable engaged with the grip is such that it is at a maximum at the tangent point where it first comes into contact with the grip drum and then gradually reduced to a minimum at the locked portion between the cantilever and the cam. The grip is so arranged that the greater the tension on the cable, the greater the grip exerted on the cable, so that there is no slippage between the grip and the cable.

Considering the test machine 10 as shown in FIGURE 1, a hydraulic or other suitable form of load applying cylinder 20 is fixed to a press frame 21 having columns 22, a base 23, and a header 24. A suitable source of pressure such as hydraulic fluid is fed to the cylinder through line 25 and the load imparted to the test specimen is measured by any conventional testing machine 26. The grips consist of a lower grip 27 and an upper grip 28.

The lower grip 27 is held by an adjustable bracket 30 having threaded columns 31 which support a header 32.

The grips 27 and 28 are identical, so that only grip 28 will be described. The grip 28 consists of a drum holder 33 and a drum 35. The drum holder and drum are desirably integral but may permissibly be of separate sections fixed together by welding, bolting, or the like. The drum holder comprises a web 36 and a flange 37.

The flange 37 has a tapped hole at 38 which receives a threaded piston rod 40 which is locked to the flange by a lock nut 41'. The longitudinal axis of the piston rod 40 is parallel to the longitudinal axis of the cable specimen being tested as later explained.

The flange 37 portion of the drum holder 33 has suitably an inner curver contour or arcuate contour 41 extending at a constant radius from a point 42 in the web 36.

60 The drum 35 comprises a rigid segment 43 and a cantilevered segment 45. The rigid segment 43 extends arcuately about the drum from a point 46 to a point 47 and is suitably integral with the web 36 throughout this arcuate length. The cantilevered segment 45 extends from point 46 to point 48. A guide segment 50 extends arcuately from the rigid segment 43 at 47.

Drum 35 has an inner circumference 51, an outer circumference 52, an end wall 53, and an end wall 54. The outer circumference has a groove 55 having sides 56 and 57 and a bottom 58. A slot 60 extends through the drum to separate the cantilever segment 55 from the guide segment 50.

An eccentric cam 65 having a shaft 66 and a clamping surface 67 is rotatably secured at its center of rotation 68 to the web 36 at 42. The cam 65 is suitably held to the web by a shoulder screw 70 which has a shoulder 71

which bears against a counter sunk hole 72 in cam 65. The shank of screw 70 has a threaded portion at 73 which engages a tapped hole 75 whose longitudinal axis coincides with point 42.

The inner circumference 51 is of constant radius with respect to point 42 and the outer circumference 52 of the drum is of constant radius with respect to the point 42. The surface 76 of clamp portion 67 is cylindrical in contour and of a knurled or roughened surface. A handle 77 is positioned in cam 65 radially from the center of rotation 68 and is secured in the shaft portion 66 at 78.

In operation, a test specimen 80, such as a cable, comprised of wire strands, is laid in groove 55 of the drum and wrapped around the outer circumference of the drum a number of times, for example, two.

The radius of the outer circumference of the drum is such that when a tensile force is brought to bear on the cable 80, the cable will extend from the drum in a tangent which is parallel to the longitudinal axis of the piston rod 40 which applies the tensile load to the grip.

After the cable is wrapped around the drum a suitable number of times, the end is brought over guide segment 50 which has a radius of curvature 81 capable of imparting a gradual turn to the cable to direct it in a tangent to the inner circumference of the cantilever segment at 82. The cable is then laid on the inner circumference 51 of the drum between the cam 65 and the drum 35. The cam 65 has been rotated at this point to allow sufficient clearance between the surface 76 and the inner circumference 51 to allow the cable to be readily put in place. The cam is then rotated clockwise as viewed in FIGURE 2 until the clamping portion 67 of the eccentric cam 65 engages the cable 80 and holds it tightly against the cantilevered segment 45 of the drum 35 on the inner circumference 51.

The lower end of the test specimen 80 is similarly engaged in lower cable grip 27. It will be seen that the cable can extend to any length at 83 since it is not necessary to have a free end of the cable to mount the cable in a grip. A load is then applied to pull the grips apart as by introducing fluid under pressure to cylinder 20 through feed line 25. As the specimen 80 is loaded, tension in the specimen tends to compress the drum radially inward since the cable is wrapped around the drum. The radial compression of the drum forces the cantilever portion 45 to bend from its anchor portion at 46 toward the cam, thus increasing the clamping force on the cable. At the same time, the drag of the cable 80 through the eccentric cam and inner circumference of the cantilever segment tends to rotate the cam so that it increases its clamping force. This interaction of the cable 80, cantilever segment 45, and cam 65 holds the cable 80 firmly. Tension in the cable is minimal at the cam lock, and reaches a maximum in the free length of cable between the grips, enhancing the probability of failure of the cable in its free length. At the conclusion of the test, the cable is readily removed from the grips by rotating the cam 65 in a counterclockwise direction as viewed in FIGURE 1 by means of handle 77.

In an alternative embodiment as shown in FIGURES 6 and 7, I show a grip which provides adjustment of the drum 135 with respect to the drum holder 133. This allows the user to mount the grips in a testing machine at a specific distance between the tangent points of the drums, and then apply an initial load to the specimen. For instance, it may be desirable to mount the grips in a testing machine at a specific distance of say 10 inches between the tangent points of the drum and then preload the cable to an initial load of for example 10 pounds. By establishing identical starting characteristics on a plurality of specimens, the results can be accurately compared.

In the description of this embodiment, common elements with the embodiment of FIGURES 1 to 5 are given the same numbers with the prefix 1 and will not be further described.

In this embodiment, the drum 135 is rotatable with respect to the drum holder 133. A web 135' is suitably integral with the anchored portion 143 of the drum 135. The web 135' has a boss 144 which acts as a pivot which engages a hole 144' in the web 136 of the housing 133. The boss 144 has a threaded extension 144² which receives a lock washer 144³ and a lock nut 144⁴. A key 185 having an arcuate surface 186 and a flange 187 passes through arcuate slot 188 in web 136. Flange 187 engages shoulder 189 of recess 190. Key 185 is held to the drum by suitable shoulder screws 191. An adjustable knob 192 having a head 193 and a threaded shaft 194 is threaded into a tapped hole 195 in the cable drum holder 133. The end of the shaft at 196 engages the arcuate surface 186 of key 185 to suitably rotate the key and drum counterclockwise as seen in FIGURE 6. A helical tension spring 197 is anchored to the key at 198 and to the holder at 199 to bias the drum in a clockwise direction as shown in FIGURE 6 against the adjustable knob.

In operation, the modified cable grips of FIGURES 6 and 7 are placed in the testing machine of, for instance, FIGURE 1 and the machine is adjusted so that the distance between the centers of rotation of the drum and hence the distance between tangent points on the test specimen will be a given distance. The adjusting knob 192 is then retracted to allow the drum 135 to rotate to a limiting position in a clockwise direction as viewed in FIGURE 6. Preferably this distance will be 15 degrees from a line parallel to the direction of force application to the grip. The cable specimen is then loaded as described in the device of FIGURES 1 to 5. The adjusting knob 192 is then rotated to bear against the key 185 at surface 186 and rotate the drum in a counterclockwise direction about its pivot 144 so as to place the test specimen under a tension load. The load imparted to the test specimen can be suitably determined by the indicator 26 on the testing machine. When the knob 192 has been rotated to impart a sufficient preload to the specimen, the drum 135 is fixed in its final rotative position and the specimen is now ready to be tested in the manner described in the device of FIGURES 1 to 5.

Desirably, the drum 135 is made to rotate through an arc of approximately 30 degrees with respect to the drum holder 133 as this provides sufficient travel to provide proper preload.

In view of my invention and disclosure, variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention what I claim as new and desire to secure by Letters Patent is:

1. In a gripping device for a cable: a drum holder having longitudinally extending mounting means; a drum having an inner and an outer circumference and having a rigid segment rigidly connected to the drum holder and stationary relative thereto and a cantilevered segment; said drum adapted to receive a plurality of cable turns on its outer circumference; said rigid segment having a tangent extending from its outer circumference in line with said longitudinally extending mounting means; said cantilevered segment extending in an arc and fixed at one end of the arc to the rigid segment wherein the cantilevered segment can flex radially with respect to the rigid segment under the force of a cable wrapped on the drum outer circumference; and an eccentric cam pivoted on the drum holder and adapted to rotate into clamping engagement with the cable at the inner circumference of the drum at the cantilevered segment, wherein the gripped cable is wrapped around the drum outer circumference and clamped between the cam and cantilevered segment inner circumference whereby the cable extends from the gripping device in line with the said mounting means and

tension on the cable flexes the cantilevered segment against the cam.

2. In a gripping device for a cable: a drum holder; a drum pivoted on the drum holder, means for rotationally fixing the drum with respect to the drum holder to impart an initial load to the cable including an adjusting knob having a head and a shaft, and a key on the drum in contact with the end of the shaft and adapted to be rotated by the adjusting knob; the drum having an inner and an outer circumference and having a rigid segment and a cantilevered segment; and an eccentric cam pivoted on the drum holder and adapted to rotate into clamping engagement with the cable at the inner circumference of the drum at the cantilevered segment, wherein the device receives a cable wound around the outer circumference of the

drum and gripped between the inner circumference of the cantilevered segment of the drum and the eccentric cam.

3. A device of claim 2 having a helical tension spring adapted to keep the key in contact with the shaft of the adjusting knob
